Warren C. Church, Hurt, Va., assignor to The Lane Company, Inc., Altavista, Va., a corporation of Virginia

Application December 5, 1958, Serial No. 53,663

Term of patent 14 years

(Cl. D33—13)

Fig. 1.

Fig. 2.

The essential features of the design are shown in the drawing in solid lines.

The back or rear of the buffet or the like (not shown in the drawing) is plain and unornamented.

I claim:

The ornamental design for a buffet or the like, as shown and described.
